TION OF CALIFORNIA

X-RAY MACHINE

Application filed November 21, 1927. Serial No. 234,670.

This invention relates to X-ray machines and particularly to portable X-ray machines.

One feature of the invention is to provide a machine of the above character that is capable of performing the work of a bedside X-ray machine in addition to that of a portable machine.

Another feature of the invention lies in the provision of a machine of the above character that has ample capacity to radiograph or fluoroscope any part of the human body.

A third feature of the invention is to provide a machine of the above character which may be moved from room to room or from floor to floor with the exertion of a minimum of effort.

A fourth feature of the invention resides in the provision of a machine of the above character that comprises a plurality of separable parts and which may be quickly and easily dismantled and conveniently carried from place to place.

Still another feature of the invention is to provide a machine of the above character that is of simple, light and strong construction and easily operated.

Other features and advantages will become apparent from the specification, taken in connection with the accompanying drawings wherein one embodiment of the invention is illustrated.

In the drawings:—

Figure 1 is a perspective view of the X-ray machine of this invention,

Figure 2 is a plan view of the base of the machine,

Figure 3 is an enlarged view in side elevation with parts broken away of the standard supporting the X-ray tube,

Figure 4 is a side view of the base of the machine,

Figure 5 is an enlarged side view with parts broken away of the standard supporting the controller,

Figure 6 is an enlarged view in side ele-

vation with parts broken away of the tube arm,

Figure 7 is a plan view with parts broken away of the tube arm shown in Figure 6,

Figure 8 is an enlarged sectional view with parts broken away taken along line 8—8 of Figure 3, and

Figure 9 is an enlarged sectional view taken along line 9—9 of Figure 3.

As illustrated in Figure 1 of the drawings, the X-ray machine 1 comprises a base 2 supporting a transformer 3 and two standards 4 and 5. The X-ray tube 6 is supported from the standard 4, whereas the controller 7 is mounted upon standard 5.

The base 2 (see also Figures 2 and 4) has legs 8 that are antifrictionally supported upon easy running casters 10. A rectangular aperture 11 is provided in the base 2. Lugs 12 are formed on the side walls of aperture 11 and extend inwardly from the four corners of this aperture for the purpose of supporting transformer 3 within this aperture. A socket member 13 is positioned near one end of the base 2 and is arranged to hold standard 4 in a vertical position. This standard and standard 5 are preferably of tubular construction. Socket member 13 has a tubular lower portion 14 that extends downwardly through a circular aperture provided in the base 2. An inwardly extending annular flange 15 is formed on the lower end of portion 14 for the purpose of supporting the standard 4 within the socket member 13.

This socket member has a flange 19 that is secured to the base 2 as by screws. The upper portion of the socket member 13 is slotted at 16 and lugs 17 are formed on the opposite sides of this slot. Lugs 17 are arranged to be drawn together by means of a screw and a wing-nut 18 for the purpose of causing the socket member 13 to grip the standard 4, thereby retaining this standard within the socket member.

A screw 20 is threaded into an aperture 90

provided in the standard 4 (see Figure 3) and engages a vertically extending slot 21 in the socket member 13. With the standard 4 supported within the socket member 13, the screw 20 engages the sides of the slot 21. This prevents the turning of the standard 4 with respect to the socket member.

From the socket member 13, the standard 4 extends upwardly through circular apertures provided in a bracket 22 (Figures 3, 8 and 9). Bracket 22 is provided with anti-frictionally mounted rollers 23 that ride upon the standard 4 and enable this bracket to be moved to any desired position upon the standard with a minimum of effort. These rollers are spaced one hundred and twenty degrees apart at the upper and lower ends of bracket 22, thereby supporting this bracket at three points on both ends.

20 A friction clamp 24 has a trunnion 25 that extends through an aperture provided in the lower portion of bracket 22. Bracket 22 acts as a fulcrum for trunnion 25. Clamp 24 surrounds the standard 4 and is urged into 25 gripping relation with this standard by a compression spring 26. A thumb lever 27 is formed upon friction clamp 24. By pressing the thumb lever 27 downwardly toward a finger rest 28, the spring 26 is compressed, 30 thereby releasing the clamp 24 from gripping engagement with the standard 4.

Bracket 22 is arranged to be locked in any desired position upon standard 4 by means of a lock 30. Lock 30 has a locking lever 32 that is pivotally mounted upon the upper portion of bracket 22. Locking lever 32 has an eccentric portion 31 that cooperates with a plunger 33. Plunger 33 is secured to one end of a compression spring 34. The other 40 end of spring 34 is secured to a locking sector 35. Locking sector 35 carries leather washers 36 that are positioned adjacent the standard 4. With the locking lever 32 in its lower position, shown in Figures 1, 3 and 9, its eccentric portion 31 compresses the spring 34 and causes the washers 36 to grip the standard 4, thereby locking the bracket 22 in position on the standard 4. By swinging locking lever 32 upwardly, its eccentric portion 31 45 moves away from the spring 34 and causes the washers 36 to disengage the standard 4 so as to release the bracket 22. Should the lock 30 be accidentally released, the friction clamp 24 will support the bracket 22 and prevent its falling.

A circular aperture 29 is provided in the bracket 22 and is adapted to receive a spreader 37. A thumb screw 38 is threaded through the wall of aperture 29 and is arranged to engage the spreader 37 so as to retain this spreader in any desired position. When the spreader 37 is not in use it may be retained by a clip 49 secured to the underside of the base 2.

65 A trunnion 39 is formed on the central

portion of bracket 22. An annular groove 46 is provided in the trunnion 39 for a purpose that will be explained later. Trunnion 39 is arranged to support a tube arm 40 (see also Figures 6 and 7). Tube arm 40 is preferably of hollow cylindrical construction and comprises a body portion 41 and a telescoping portion 42. A cylindrical plug 43 is secured within the body portion 41 of tube arm 40 and has a longitudinal aperture 44 to receive the trunnion 39. Tube arm 40 is retained on the trunnion 39 by a headed pin 45 that is spring pressed into the annular groove 46. A hand screw 47 has its shank threaded through an aperture in the tube arm 40 and is arranged to engage the trunnion 39 so as to lock the tube arm in position on this trunnion. By releasing the hand screw 47 and pulling the headed pin 45 outwardly so as to clear the groove 46, the tube arm may be removed from the bracket 22.

70 A sleeve 48 is secured to the body portion 41 of the tube arm and has a reduced end that surrounds the telescoping portion 42. Telescoping portion 42 may be moved longitudinally with respect to the sleeve 48, thereby enabling the X-ray tube 6 to be positioned at varying distances from the standard 4. A key 50 and a bushing 51 are secured to the telescoping portion 42 and cooperate with the body portion 41 to guide the telescoping portion during its longitudinal movement. The telescoping portion 42 is limited in its outward movement by a bushing 51 striking a stationary sleeve 52. The sleeve 48 and the body portion 41 are slotted at 53 and lugs 54 are formed on the sleeve 48 at the opposite sides of this slot. Lugs 54 are arranged to be drawn together by means of a hand screw 55 for the purpose of causing the sleeve 48 to grip the telescoping portion 42, thereby retaining this portion of the tube arm in any position desired. Telescoping portion 42 has three spaced annular scarifications at 59 to enable the making of stereoscopic exposures. The outer scarifications are spaced an amount equal to the spacing of the normal human eyes.

75 A disk 56 is fixed to the end of the telescoping portion 42 and coacts with a similar disk 57 forming a part of a universal coupling member. A hand screw 58 has its shank extending through aligned central apertures provided in the disks 56 and 57. Hand screw 58 may be loosened to permit relative angular movement between these disks or it may be tightened to lock them fixedly together. Disk 57 is formed integral with a disk 60 that is positioned at right angles to disk 57. A tube base 63 is attached to the disk 60 by a friction clamp 61. Clamp 61 comprises a screw 62 carrying a spring washer (not shown) that bears against the tube base 63. Screw 62 extends 80

through an aperture in the tube base 63 and is threaded into disk 60. Friction clamp 61 permits the tube base 63 to be turned angularly with respect to the disk 60.

5 Segmental clamps 64, 65 and 66 having fibre sleeves 67 are arranged to secure the shield of the X-ray tube 6 to the tube base 63. Clamp 64 is fixed to the tube base 63, whereas clamps 65 and 66 may be adjusted 10 radially with respect to the central axis of this base by means of screws 69. Tube base 63 has a filter 68 preferably of aluminum.

15 The anode conductor 70 (Figure 1) and the cathode conductors 71 and 72 of the X-ray tube 6 pass under the spreader 37 to reels 73, 74 and 75 respectively, carried by a spreader 76. Spreader 76 is mounted upon standard 4 and has a shank (not shown) extending into a socket 77 (see Figure 3) provided in a plug 78 that is positioned in the upper end of this standard. Plug 78 is formed so as to permit the spreader 76 to be mounted in only one position on the standard 4. The spreader 76 may be removed 20 from the standard 4 by raising the spreader so that its shank disengages socket 77.

25 A cable 80, having a single conductor, connects the reel 73 to one high tension terminal of the transformer 3 for the purpose of transmitting current to the anode of the X-ray tube 6. A cable 81, having two insulated conductors, connects the reels 74 and 75 to the other high tension terminal of the transformer 3. The conductors of cable 81 30 transmit the heating current for the cathode of the X-ray tube 6. The insulation of cables 80 and 81 is preferably of pure Pará rubber, and is of sufficient dimension to permit the handling of these cables while the machine is in operation. The upper conductor terminals of cables 80 and 81 hook over shanks formed on the several reels 73, 74 and 75 while the lower conductor terminals of these cables plug into sockets provided in the 35 transformer 3, thereby facilitating the rapid connection or disconnection of these conductors.

40 A socket member 82 is positioned near one end of the base 2 and is arranged to hold standard 5 in a vertical position. Socket member 82 is similar to socket member 13 and has its lower portion 83 extending through an aperture provided in the base 2. A screw 84 (Figures 2, 4 and 5) is threaded through an 45 aperture provided in the lower portion 83 and extends into a longitudinal slot 85 cut in the lower end of standard 5. Screw 84 cooperates with slot 85 to prevent the turning of standard 5 within the socket member 82. 50 Standard 5 is retained within socket member 82 by tightening the wing-nut 86. A hook 87 is secured to the standard 5 for the purpose of supporting the foot control switch 88 when the X-ray machine is not in use.

55 A longitudinal slot 90 is provided in the

upper end of standard 5. A socket member 91 (Figure 1) is secured to the bottom of the controller 7. Socket member 91 has a screw (not shown) that extends into the slot 90 when the controller 7 is mounted upon the 76 standard 5. The coaction of this screw with slot 90 retains the controller 7 in proper angular position with respect to the standard 5. A wing-nut 92 may be adjusted along a screw 75 for the purpose of causing the socket member 91 to grip the standard 5, thereby retaining the controller 7 upon this standard. Legs 93 formed upon the controller 7, enable this controller to stand upon a horizontal surface when it is not mounted upon the 80 standard 5.

85 The metal casing of the controller 7 completely encloses the controlling apparatus including an auto transformer for regulating the voltage output of the transformer 3. A cable 99 electrically couples the controller 7 to transformer 3. It is possible, by using a transformer 3 weighing but sixty pounds, to obtain any milliamperage from zero to thirty at a pressure equivalent to a spark gap 90 varying from three to five inches. All meters, switches and controls are conveniently mounted on the top panel 94 of the controller 7. A lever 95 enables the rapid selecting of an X-ray tube voltage of a value corresponding to either a three inch or a five inch spark gap. A similar lever may be used to select an X-ray tube current of either five or thirty milliamperes. The five milliamperes current is used in fluoroscopic work whereas the 100 thirty milliamperes current is used in radiography. The machine is designed so that its plug 98 may be coupled directly to a suitable source of power. As the controlling apparatus and circuits form no part of the present 105 invention they would appear to require no further description.

110 Handles 96 and 97 are provided on the controller 7 and transformer 3, respectively, to enable the ready carrying of these parts from place to place.

115 In operation, the X-ray tube 6 may be placed at any height desired by merely moving bracket 22 along the standard 4. Thus the X-ray tube may be lowered to the floor and placed under a bed or table or raised to chest height. The tube arm 40 may be swung about the standard 4 to any angle desired, and when the machine is not in use, this arm may be positioned over the controller 7 making a very 120 compact arrangement. The telescoping feature of the tube arm permits the X-ray tube to be placed at varying distances under a bed or table as for setting fractures. In stereoscopic work the telescoping portion of the 125 tube arm is adjusted so that exposures are taken with the outer scarifications 59 in alignment with the end of sleeve 48. The universal coupling member connecting the tube arm 40 to the tube base 63 enables the X-ray tube 130

to be readily adjusted to any angle that may be desired.

The bracket 22 and the tube arm 40 may be counterbalanced if desired, by a counterweight positioned within the standard 4. If such a counterweight is employed, the friction clamp 24 may be omitted.

Inasmuch as the spreader 37 is carried by the bracket 22, the conductors 70, 71, and 72 are always properly spaced regardless of the positions the X-ray tube may take along the standard 4. The reels 73, 74 and 75 maintain these conductors taut at all times.

The thorough insulation of cables 80 and 81 enables the operator to work around the machine with great freedom and eliminates the common danger of shock from these high tension leads.

The controller 7 is positioned where it will enable the operator to regulate the X-ray tube with the greatest convenience. If desired, an automatic timing device may be included within the controller 7 for the purpose of properly timing and limiting the exposures used in radiographic work. Also a current stabilizer, as of the electro-magnetic type, may be mounted under the base 2 for the purpose of maintaining a constant voltage supply for the X-ray tube, thereby obtaining a uniform output from this tube. The low center of gravity of the transformer 3 enables the base 2 of the machine to be made of extremely light material such as aluminum. The casters 10 enable the moving of the machine from room to room with the application of but a finger's pressure.

It is to be noted that the machine is of extremely substantial construction throughout. It may be taken apart by merely loosening four screws 18, 86, 92 and 47 and as readily put together again. The several parts of the machine are especially constructed so that they may be carried from place to place without the use of a carrying case. Such a case, however, may be used if desired. In the event that a carrying case is employed, the standard 4 is divided midway of its length, and the two halves so formed are constructed so that they may be readily connected together or disconnected.

It will be noted that the various parts of the machine are constructed so that it is impossible to assemble them incorrectly. For example, standard 4 can only fit into socket 13 and standard 5 into socket 82.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. An X-ray machine comprising a base, an X-ray tube, a standard removably attached to said base, a bracket antifrictionally mounted on said standard, a friction clamp carried by said bracket and adapted to hold said bracket in a plurality of positions on said standard, means for locking said bracket in any one of said plurality of positions, a tube arm removably attached to said bracket, a tube base supporting said X-ray tube, a universal coupling connecting said tube base to said tube arm, a transformer for supplying current to the X-ray tube, and a controller for regulating the current supplied by said transformer.

2. An X-ray machine comprising a base, an X-ray tube, a standard removably attached to said base, a bracket antifrictionally mounted on said standard, a friction clamp adapted to hold said bracket in a plurality of positions on said standard, means for locking said bracket in any one of said plurality of positions, a tube arm removably attached to said bracket, said tube arm having a telescoping portion, means having a universal connection with the telescoping portion of said tube arm and supporting said X-ray tube, a transformer removably positioned within an aperture in said base, and a controller removably mounted upon said base, said controller and transformer being electrically interconnected with each other and electrically connected with the X-ray tube.

3. An X-ray machine comprising a base, an X-ray tube, a transformer mounted on said base, a standard mounted on said base adjacent one wall of said transformer, and supporting said X-ray tube, a second standard mounted on said base adjacent an opposite wall of said transformer, said second standard terminating below the top of said first standard, a controller mounted on top of said second standard within convenient reach of the machine operator, said controller and said transformer being electrically interconnected for the purpose of controlling the energization of said X-ray tube, conductor supporting means carried by said first standard, and electrical conductors connected with said conductor supporting means and interconnecting said transformer with said X-ray tube.

4. An X-ray machine comprising a base, an X-ray tube, a transformer mounted on said base, a standard mounted on said base adjacent one wall of said transformer, a bracket mounted on said standard and supporting said X-ray tube, said bracket being adjustable up and down said standard at will, a second standard mounted on said base adjacent an opposite wall of said transformer, said second standard terminating below the top of said first standard, a controller mounted on top of said second standard within

convenient reach of the machine operator, said controller and said transformer being electrically interconnected for the purpose of controlling the energization of said X-ray tube, a spreader mounted on top of said first standard, a second spreader carried by said bracket, and leads supported from said spreaders and interconnecting said transformer with said X-ray tube.

10 In testimony whereof, we have signed our names to this specification.

GEORGE L. BUSH.
ALBERT E. BUSH.
